UNITED STATES PATENT OFFICE.

CHARLES MOUKOS, OF MILWAUKEE, WISCONSIN, ASSIGNOR TO FRANK J. MATCHETTE, OF MILWAUKEE, WISCONSIN.

PNEUMATIC CLEANING-TOOL.

No. 882,574.

Specification of Letters Patent.

Patented March 24, 1908.

Application filed April 8, 1907. Serial No. 366,954.

To all whom it may concern:

Be it known that I, CHARLES MOUKOS, a citizen of the United States, and residing at Milwaukee, in the county of Milwaukee and 5 State of Wisconsin, have invented certain new and useful Improvements in Pneumatic Cleaning-Tools, of which the following is a specification, reference being had to the accompanying drawing, forming a part thereof.

10 My invention relates to improvements in pneumatic cleaning tools and more especially to the class of handles adapted for use with tools employing air as a cleaning agency in conjunction with the tool proper.

15 The objects of my invention are to provide an improvement in means whereby a tool handle when attached to the tool may be adapted to turn to any desired position out of the normal, should it be desired to use the 20 tool for sweeping in places difficult to reach when the handle is held in the ordinary sweeping position and at the same time provide an air tight joint between the handle and tool that will preserve a clear unobstructed air passage there between in all positions of the handle.

Other objects and novel features of construction will be pointed out and described in the specification following and are illustrated in the drawing accompanying and forming a part of said specification wherein my improved means for connecting a tool and tool handle are shown in connection with a pneumatic cleaning brush.

35 In the accompanying drawing, Figure 1 is a central section of a brush provided with my improved joint for securing a handle to the body proper of the brush; Fig. 2 is a side elevation of the device showing the clamping member in section and the external appearance of the joint; and Fig. 3 is a detail view showing the structure of the clamping member.

In the drawing, a brush 1 of a construction common to pneumatic cleaning brushes is provided with a skirt or casing 2, which is preferably of a flexible material impervious to the air, secured to a body 3 through which extends a nozzle 4 provided with a bore 4'. 45 Set upon the upper face of the body portion 3 of the brush 1 is a plate 5 which preferably is circular in formation and is secured in the present instance by means of screws 6.

50 It is to be understood that the plate 5 may be secured in any suitable manner to the

body of the brush, other means beside the screws herein shown being suitable for the purpose.

Integral with the plate 5 and curving upwardly and outwardly therefrom is a barrel 60 7 provided with a bore 7' which latter is largest towards the outer end of the member 7 and is contracted adjacent to the nozzle 4 so that the internal bore 4' of the nozzle 4 and the bore 7' of the member 7 form a continuous passageway, the faces of each of the members 4 and 7 lying flush with each other and offering no protruding parts that may collect dust or interfere with the free passage of the air through the channel or bore in said 65 member.

At the outer end of the member 7 is formed an annular rim 8, this being preferably formed integral with the member 7. The rim or flange 8 is provided with a beveled 75 exterior face 9 which slopes rearwardly from the outer face of the member 7 toward the main body thereof. This rim or flange 8 is further provided with a rabbet 9' which forms a seat in the outer face of the member 80 7, the purpose of which will hereinafter be more specifically set forth. To coöperate with the member 7 and the flange 8 above described, there is provided a barrel 12 which is similarly to the member 7 provided with a 85 rim or flange 13 having a beveled face 13'. This flange 13 is further provided with a projecting face or shoulder 14. The object of this projecting face 14 is to seat within the rabbet 9' of the member 7 when the parts are 90 secured in operative position.

It is to be noted that when the parts are brought together in operative relation that the projecting rim or shoulder formed on the outer face of the member 12 seats in the rabbet 95 of the member 7 in such a manner as to form a flush joint. The projecting portion 19 of the member 7 forms a bearing face which rests against the recessed portion of the member 12, the interior faces of each of 100 these portions lying flush with each other and not in any way obstructing the bore of the barrel thus forming practically an air tight joint and also one offering no obstruction to the free passage of air and of dust and dirt 105 through the bore of the brush handle.

The angular relation of the meeting faces of the member 12 and the member 7 to the respective members is such as to insure upon the rotation of the member 12 a radical 110

change in the position of the barrel or handle 17 which is adapted to enter the member 12 within the recessed portion 18 of said member 12. This handle 17 is so disposed within the member 12 as to have its bore in alignment with the bore of the member 12, the interior face of said member 17 lying flush with the interior unrecessed face of the member 12.

10 By a rotation of the handle 17 in either direction from its position in Fig. 2, and consequently the member 12, the former can be made to assume various positions intermediate the normal sweeping position illustrated 15 in Fig. 2, and the horizontal position shown in Fig. 1, for cleaning under furniture and other places not readily accessible with a handle disposed relative to the tool body, as seen in Fig. 2.

20 In order to secure the brush handle to the member 7, the member 12 is adapted to be clamped to the member 7 by means of a clamping ring 10 formed of resilient material preferably, and provided with lugs 11', 11' 25 which are adapted to be drawn together by the screw 11. The inner face of this annular clamping ring 10 is provided with a recess in this instance shown to be a recess of about one hundred and twenty degrees angle which 30 is adapted to fit over the outer beveled faces 13' and 9' of the rims 8 and 13 of the members 7 and 12. It is understood that by tightening the screw 11 the clamping ring 10 more firmly secures the members 7 and 12 in 35 locked position and similarly by loosening the screw 11 these members may be permitted a freer rotation or entirely removing the clamping ring the members may be separated.

40 The ring 10 is normally loosely clamped about the meeting faces of the members 7 and 12, so that while insuring an air tight joint, it does not cause too great a friction between the parts, but permits an easy and 45 free movement therebetween.

For the purpose of securing the barrel or handle 17 within the member 12 there are provided lugs 15, 15 upon the outer surface of the member 12 which are adapted to be 50 drawn together by means of the thumb screw 16. This clamping member consisting of the lugs 15, 15 and the thumb screw 16 secures the member 17 in locked engagement within the member 12 and should it be desired to remove this member 17 the clamping member just described is loosened to permit of the easy removal of the member 17.

55 The operation of the device herein described is readily apparent from the foregoing description but may be summed up briefly as follows. When the parts are assembled member 12 through means of its projecting rim 13, seats within the recess 9 of the member 7 with its bearing face 20 resting 60 upon the bearing face 19 of the member 7.

The clamping ring is then placed in operative position and is tightened to secure together, and at the same time permit a free movement of the parts, the handle 17 and the member 12, the handle being ordinarily 70 at the normal angle convenient for sweeping as shown in Fig. 2. When it is desired to sweep in places not readily accessible in the normal position of the handle, the handle together with member 12 is turned until such 75 a position or angle is reached as will enable the operator to readily sweep the portion of the floor desired. After sweeping this portion of the floor it is of course understood that the handle is turned back to its normal 80 position, this being done without the operator being bothered with any adjustments of screws, clamping means or other parts. These adjustments in the position of the handle are accomplished by the movement 85 of the operator's arm in sweeping, and take place as often as the need arises in the course of operation of the tool. In the actual use of the tool, the clamping ring is normally adjusted to permit of an easy and free movement 90 between the two barrels. This freedom of movement allows the handle to be rotated so as to assume various positions between the normal sweeping position of Fig. 2 and that shown in Fig. 1, in harmony with 95 the movements of the operator's arm, and without interruption of the operation of sweeping, for the purpose of adjusting the handle. Owing to the angular relation of the meeting faces of the two barrels, the 100 handle receives upon rotation two adjustments relative to the brush, that of its vertical angle and also that of its horizontal angle thereto, so that beside taking any desired vertical position, it is turned to one side 105 or the other to take up any desired horizontal angle with the brush. The handle is thus self-adjusting in actual use, to the movement of the arm of the operator, and freely adapts 110 itself to the various changes in position necessarily assumed by the operator's arm in sweeping beneath and around sundry articles of furniture and other objects.

The special structure of the joint which permits of the accomplishment of the objects herein-before set forth has been described and the operation of the brush handle provided with this special construction of joint fully set forth. It is understood that only the preferable form of this joint 115 constituting my present invention has been described and that various modifications may be introduced into details thereof without in the least departing from the spirit and scope of my invention.

Having fully described my invention and its operation what I claim and desire to secure by Letters Patent of the United States is:

1. In a pneumatic cleaning tool, a tubular 130

member having its end face cut away at an oblique angle, and provided with an annular rim, a rotatable barrel having its end face cut at an oblique angle and provided 5 with an annular rim, said barrel being mounted for rotation upon the tubular member, the annular rims and angular end faces of the parts interfitting and adjustable means for securing these parts in operative 10 position and to permit rotation of the barrel about the tubular member, substantially as described.

2. In a pneumatic cleaning tool of the character described, a tubular member having its end face cut at an oblique angle, an annular rim formed thereon and provided 15 with a rabbet, said rim being provided with a projecting portion, a rotatable barrel having its end face cut at an oblique angle and 20 provided with an annular rim having a projecting portion and a recess, said projecting portion of the rim being adapted to seat within the rabbet of the tubular member when the parts are brought into operative 25 relation, and means for loosely clamping said parts in operative relation to permit the rotation of said barrel to vary its horizontal and vertical angular relation to the tubular member.

30 3. In a pneumatic cleaning tool, a tubular member having its end face cut away at an oblique angle, a barrel having its end face cut at an oblique angle and rotatably mounted upon said tubular member, an adjustable

clamping means for securing the barrel upon 35 the tubular member, said clamping means permitting the free rotation of the tubular member, and a tubular handle mounted within said barrel.

4. The combination, in a pneumatic cleaning tool, of a tubular member, a barrel rotatably mounted upon said tubular member, the end faces of the tubular member and barrel being cut away at oblique angles and contacting, and adjustable clamping means 40 for holding said barrel in rotative relation to the tubular member, and permitting the horizontal and vertical angular adjustment of the barrel with respect to the tubular member, substantially as described. 45

5. In a pneumatic cleaning tool, a tubular supporting member mounted upon the tool, an annular rim disposed at the outer end of said supporting member, said rim being provided with a bearing face and a rabbet, a 50 barrel provided with a rim coöperating with the rim of the supporting member and seating within the rabbet thereof and against the bearing face of said supporting member rim, and means for loosely clamping said barrel 55 and supporting member in operative relation, to permit free rotation of said barrel.

In witness whereof I hereto affix my signature in presence of two witnesses.

CHARLES MOUKOS.
